UNITED STATES PATENT OFFICE

JAMES R. HUGHES, OF SOUTH BEND, INDIANA, ASSIGNOR TO THE STUDEBAKER CORPORATION, OF SOUTH BEND, INDIANA, A CORPORATION OF NEW JERSEY

DESIGN FOR A HEAD LAMP

Application filed May 1, 1930. Serial No. 35,454. Term of patent 14 years.

To all whom it may concern:

Be it known that I, JAMES R. HUGHES, a citizen of the United States of America, and resident of South Bend, in the county of St. Joseph and State of Indiana, have invented a new, original, and ornamental Design for a Head Lamp, of which the following is a specification, reference being made to the accompanying drawing, forming a part thereof.

In the drawing,

The design illustrated includes a casing which is oval in front elevation, the rim being formed substantially as shown in Figure 3, and the ornamental members at the top of the casing being formed to converge into the casing forwardly of the apex thereof.

I claim:

The ornamental design for a headlamp substantially as shown and described.

Signed by me at South Bend, Indiana, this 28 day of April, 1930.

JAMES R. HUGHES.
